UNITED STATES PATENT OFFICE.

WILLIAM CLYDE WILLIAMSON, OF BROOKLYN, NEW YORK, ASSIGNOR TO BRIGGS BITUMINOUS COMPOSITION COMPANY, INC., OF NEW YORK, N. Y., A CORPORATION OF NEW YORK.

FLOORING FOR REFRIGERATOR RAILWAY CARS.

Application filed November 17, 1925. Serial No. 69,632.

The invention relates to an improved water tight, acid proof and sanitary flooring for railway cars, particularly, refrigerator cars, so laid and constructed as to effectually resist the stresses and strains brought upon it when the car is in motion. It is, of course, well known that the walls, icebox bulkheads, stanchions and drain pipes, all of which go to make up the construction of a freight car, particularly of the refrigerator type, tend to sway and move with respect to the flooring when the car is in use, so that in a short time cracks and crevices will occur at the lines of juncture between the several parts above mentioned. The water from the melted ice, and also the dregs from the various kinds of freight will soon enter these cracks and crevices and seep through them down to the wood flooring and the insulation at the ice-box ends of the car thus not only causing the latter to deteriorate and decay, but in cold weather the water soaked insulation oftentimes freezes and thus loses its insulating value. The principal object, therefore, of my invention is to provide a surface structure for railway car floors and similar flooring which will be strong and tough and which will effectively resist the strains and stresses to which such platforms are subjected, thus remaining intact, forming practically a hermetical seal between the freight space and the lowermost construction of the floor of the car. Another object of the invention is to so construct the surface of the flooring that should the main body become cracked in the areas of its surface most subjected to the strains and stresses, that it will maintain its normal surface condition to the end that vegetable matter and water from melted ice, and all other deleterious matter will be prevented from entering the cracks, and thus the life of the flooring is prolonged over that of other floors not constructed in accordance with my invention.

Another object of the invention is to provide a surfacing for floors of railway cars which consists of a strong elastic composite structure and particularly designed to prevent moisture or deleterious matter from reaching the heat insulation which is provided in refrigerator cars and thereby prevent the said insulation from rotting or

from freezing, or otherwise be put into a condition under which the insulation would not perform its full function. 55

Another object of my invention is to provide armor plates or reinforcements on the surface of the flooring at the door openings to resist undue wear at these areas. 60

Other objects will appear from the subjoined specification and claims.

Referring to the drawings forming a part of this specification: 65

Fig. 1 is a plan view of one end of a refrigerator railway car showing an embodiment of my invention as applied to the flooring of that car, the sides of the car being shown conventionally in horizontal cross section. 70

Fig. 2 is a vertical sectional view, broken away, taken along the line 2—2 of Fig. 1.

Fig. 3 is a vertical sectional view taken along the line 3—3 of Fig. 1. 75

Fig. 4 is a plan view, broken away, of an end of the car as shown in Fig. 1.

Fig. 5 is a section on line 5—5 of Fig. 1.

Fig. 6 is a section on line 6—6 of Fig. 1, the inner wall only of the side of the car being shown. 80

It should be stated at the outset that in the interest of clearness, Fig. 1 is a broken view of practically half of the flooring of the car, the other half being similar thereto in construction. So also Fig. 4 represents a plan of either end of the car flooring, the walls or sides of the car being shown conventionally in horizontal cross section, the floor covering being broken away at the corners to show the construction underneath. 85

In Fig. 3 the grating which is usually installed in the refrigerating sections is shown only in cross section, this grating in practice being duplicated at the other end of the car. In the interest of clearness, however, the grating is not shown in Figs. 1, 2 and 4, because, if illustrated, the grating which is not a part of my invention would cover up the construction pertaining to the invention herein disclosed and claimed. 95

In the drawing, A represents the usual sills of a railway car, B the sides, C the inner wall, D the heat insulation, E the stanchions or posts, F the shoes for supporting the stanchions, G the supporting beams for the grating bars H; I are the drains in the refrigerator ends of the car and K the flooring 100

in the main body of the car, all of which are of the usual construction and conventionally shown and well understood by those skilled in this art.

5 In the drawing, 10 is a composition floor covering made preferably of a mixture of high grade asphalt and very fine sand, the said composition being laid on top of the flooring in the main body of the car and on 10 the top of the insulation in the refrigerator ends of the car. This floor covering composition is preferably approximately 1 inch in thickness and it extends upwardly at the ends and sides of the car for a distance of 15 approximately 3 inches.

In laying the surface flooring strips of wood 20 and 21, each being triangular in horizontal cross section, are secured on the insulation below the ice-boxes in the longitudinal corners between the insulation and the inner walls of the car by means of spikes 22 driven through the strips and into the insulation, the strips being positioned at a distance of about $\frac{1}{16}$ th of an inch in width 25 from the side walls of the car.

Similar strips 30 and 31 run longitudinally of the car from ice-box bulkhead to ice box bulkhead, except for the spaces necessary to form the doors of the car, and these 30 strips fit into the corners formed by the floor of the car and the inner walls thereof, and are likewise secured to the floor by spikes 32 and so positioned that there are spaces or crevices approximately $\frac{1}{16}$ th inch wide between the outer edges of the triangular strips 30 and 31 and the inner walls of the car.

Across each end of the car a triangular strip of wood 35 is secured (one only being shown). This strip borders the end of the walls formed underneath the grating of the ice-box. The composition is then laid over the floor of the main body of the car and over the insulation underneath the ice-boxes 40 at a thickness of approximately 1 inch, and it is extended upwardly over the hypotenuse of the triangular strips 20, 21, 30 and 31 for a distance of 3 inches, but does not contact with the side walls and end corner strips 45 35 of the car, the open space between them being about $\frac{1}{16}$ inch in width. Each of these spaces or crevices is filled with a bituminous binder designated at 40, 41 and 42, which binder, because of its resiliency, 50 will give when the parts of the car are caused to vibrate to and from each other when the car is in motion and thus will always provide a hermetical seal between the edges of the strips and the edges of the composition 55 flooring and the sides and ends of the car. So also, in the spaces about $\frac{1}{4}$ inch wide, formed around the drains, a bituminous binder 43 and 44 is poured so that in the 60 event of movement of the drains with respect 65 to the composition flooring, the bituminous

binder will always remain intact and prevent crackage between the composition flooring and the drains. Also the bituminous binder fills the spaces 43, 44, 45, 46 and 47 formed between the edge of the composition 70 flooring and the metal supports for the stanchion of the ice-box bulkheads, likewise to prevent crevices being formed therebetween, so that water and other matter will not ooze from the surface of the composition 75 down to the flooring or the insulation. The widths of these spaces are about $\frac{3}{8}$ inch.

At the junction of the side flanges of the composition formed entirely around the car, layers of bituminous binder 50, 51 and 52 are placed, this being also of a resilient character so that at the corners where the strains and stresses are great the binder will not crack and will thus form a surface at the corners which will always remain intact, thus preventing water from the melting ice and material from the freight which is packed in the car from entering any cracks and causing deterioration of the composition. 85

An effective binder used as expansion joints is an asphalt material having a melting point of 165/190 degrees F. penetration at 100 gram at 77 degrees F. 30/40, penetration at 200 gram at 32 degrees F. 18, the specific gravity 1.01. 90

Referring more particularly to Figs. 1 and 5, the door openings are indicated at O, the sides of which are preferably lined with sheet metal 70 and 71, the sills being reinforced by metal plates 72 and 73. Just inside of the door opening are placed metal plates 74 and 75 which extend the width of the door and project inside a short distance, as clearly shown, to protect the sloping edges 76 and 77 of the composition at the doors from undue wear occasioned by the trucks which are frequently used when loading or unloading the car. 100

As changes of constructions could be made within the scope of my invention, it is intended that all matter contained in the above description or shown in the accompanying drawings be interpreted as illustrative and not in a limiting sense. 110

Having thus described my invention what I claim as new and desire to secure by Letters Patent is:

1. In a railway car, the combination of walls, a supporting floor, strips on said floor having one face slightly spaced from said walls, a hard, waterproof layer on said floor extending upwardly on said strips to provide a narrow space between the edge of said layer and said walls, and a resilient 120 filler in said space between said walls and said strip and the adjacent edges of said layer. 125

2. In a railway car, the combination of walls, a supporting floor, strips of triangu- 130

lar cross section on said floor having one face slightly spaced from said walls, a hard, waterproof layer on said floor extending upwardly on said strips to provide a narrow space between the edge of said layer and said walls, and a resilient filler in said space between said walls and said strip and the adjacent edges of said layer.

3. In a railway car, the combination of 10 walls, a supporting floor, strips of triangular cross section in said floor having one face slightly spaced from said walls, a hard, waterproof surface layer on said floor extending upwardly on said strips to provide 15 a narrow space between the edge of said layer and said walls, and a bituminous binder in said space between said walls and said strip and the adjacent edges of said layer.

20 4. In a railway car, the combination of a hard, waterproof floor surface layer having upwardly inclined edge portions, a flat supporting surface for said layer inclined slightly upwardly toward the walls of said 25 car to support said upwardly inclined portions of said layer, and a resilient filler between and separating the walls of said car from the edges of said layer.

5. In a railway car, the combination of 30 walls, a flat floor having its edge portions inclined upwardly, a hard, waterproof surface layer covering said floor and said upwardly inclined edge portions, and a resilient filling between and separating the edge 35 of said floor and its surface layer from said walls.

6. In a railway car, the combination of 40 walls, a composition floor having its edge portions inclined upwardly, a bituminous 45 filler between and separating the edge of said floor from said walls, and a layer of bituminous binder on said floor covering the

angle between the flat and the upwardly inclined portions.

7. In combination with a hard, waterproof car floor covering comprising a body portion and a side flange portion, a bituminous binder covering the junction of said body and flange portions. 45

8. In combination with a hard, water-proof car floor covering comprising a body portion and an upwardly inclined side flanged portion, a bituminous binder covering the junction of said body and flanged portions, car walls, and a bituminous binder between 50 and separating the edge of said floor covering from said walls. 55

9. In a refrigerator railway car, the combination of inner walls, heat insulating flooring, strips secured to said flooring and spaced from said inner walls, a hard, waterproof floor covering on said flooring and strips having its side edges spaced from said inner walls, and a bituminous binder in the space between said strips and walls and between said floor covering and walls to prevent the formation of cracks thereby preventing moisture on the floor covering from reaching said flooring. 60 65

10. In a railway car, the combination of 70 walls, a supporting flooring, a floor of asphalt and sand composition having its edges slightly spaced from the inner surface of said walls, and a filling of resilient material impervious to moisture in the space between 75 said walls and floor.

11. In a car having a floor and stanchions extending downwardly and supported on said floor, a hard, waterproof surface layer on said floor and slightly spaced from said 80 stanchions, and a bituminous binder filling the space between said floor and stanchions to provide a liquid-tight seal therebetween. 85
